[57] ABSTRACT

To hold a counter anvil in place in the percussion tube of the lamp, a headed pin forming the anvil is supported in the cap-shaped closed end of the tube. The anvil abuts the tube end with its head. The head length is about twice its diameter so that the contact surface is sufficiently large for centering of the anvil inside the tube. The anvil portion of the pin extends in the percussion zone and carries an ignition material. The diameter of the anvil portion is selected such that there remains a sufficiently large gap between anvil and tube.

FIG. 1

FIG. 2

PERCUSSION TYPE PHOTOFLOSS LAMP

The present invention relates to photoflash lamps which comprise a light-transmissive envelope containing combustible material and a combustion-sustaining substance, and on which a mechanically releasable ignition or primer is provided, comprising a small metal tube sealed into the envelope. The tube is in communication with the interior of the envelope; the end thereof which projects externally of the envelope is closed and contains a percussive igniting material.

It has been proposed to apply the igniting material to a wire which is secured inside the tube and functions simultaneously as a carrier for the substance and as an anvil. The wire end is thickened to form a head which is used for preliminary centering when inserting it in the tube and for securing it therein. At about half its length, the wire is provided with three or four lugs which may be formed, for instance, by beads and which are used to center the wire in the tube. The length of wire extending between head and lug is coated with igniting material.

The wire is usually coated by immersing it in ignition paste. The resulting coating on the wire head is undesirable and, consequently, is removed by wiping it off in an additional working step. Due to the required lugs and the coating procedure with subsequent wiping off, manufacture of the anvil becomes very complex; it is therefore important for simplification of the manufacturing process and price reduction, to develop a more simple anvil design.

SUBJECT MATTER OF THE INVENTION

Inside the metal tube in the region projecting externally of the lamp envelope, a headed metal pin is disposed to function as an anvil; its head is supported and centered inside the tube. The pin section extending in the percussion zone is of smaller diameter than the head, and is coated with an ignition paste e.g., applied by dipping, while holding the pin on the head.

The head of the anvil has a length of up to about two times its diameter to insure satisfactory centering of the metal pin in the tube even without the provision of additional lugs at half its length. Since that portion of the anvil previously provided with lugs may now be omitted, the length of the anvil is reduced. This permits not only a reduction in length of the photoflash lamp but also of a possible fixture such as, for example, a flash-cube. The headed pin anvil permits coating with igniting material by immersion dipping while, the head is supported and thus kept free of coating. It will therefore remain free of coating material and not even have a thin film, or residues, or traces thereon.

The invention will be described by way of example with reference to the accompanying drawings, wherein:

FIG. 1 is a part and vertical section of the ignition device;

FIG. 2 is another embodiment of the ignition device, partly in section.

The ignition device illustrated in FIG. 1 for mechanically ignitable photoflash lamps comprises a tube 1 which is deep-drawn from copper sheet and, is capped off at its closed end 2. The open end 3 of tube 1 is slightly conically expanded which considerably improves sealing into the glass envelope 4 shown in fragmentary form only. An anvil 5, in form of a headed pin

is introduced in the tube e.g. by dropping it in. Head 6 of anvil 5 is locked inside the cap-shaped end 2. The head length is about twice its diameter; thus the contact surface between anvil 5 and tube 1 is relatively large to ensure centering of the anvil within the tube.

Starting from head 6, the anvil 5 tapers towards section 7 extending across the percussion zone to a diameter which is slightly smaller than that of head 6. Section 7 extending across the percussion zone is coated, for instance, by immersion with the percussive igniting material 8. The difference in diameter between head 6 and section 7 extending across the percussion zone is selected such that there remains a gap of at least 50μ between coated anvil and tube 1 even when the thickness of coating of the igniting material is 150μ . When immersing anvil 5, the head 6 remains uncoated because the anvil can be supported at its head portion.

After insertion by dropping the coated anvil 5 head first, into the tube, it is locked in tube 1 by indenting the tube, e.g., forming a ring-shaped groove 9 adjacent head 6 where the latter merges with section 7 extending across the percussion zone.

As is to be seen from FIG. 2, section 10 of the anvil extending across the percussion zone may be of slightly conical design whereby the flame generated upon percussive ignition viz. the hot particles ejected from the tube are directed more precisely at zirconium shreds (not shown) contained in glass envelope 4.

I claim:

1. In a photoflash lamp a light-transmissive envelope (4) which contains combustible material and a combustion-sustaining substance,

a metal tube (1) sealed in the envelope (4), the tube being in communication with the interior of the envelope and having a percussion zone intermediate its length, the end (2) of the tube projecting externally of the envelope being closed; and anvil means (5) carrying percussive igniting material in the tube,

the improvement wherein

the anvil means comprises a pin (5, 6, 7) disposed in the tube, the pin having a head (6) and an anvil section (7), the head being supported at the closed end (2) of the tube (1) and being in centering engagement inside the tube solely by engagement of the head (6) and the closed end (2) of the tube (1), said tube being indented (9) immediately above the head of the anvil, and locking the head in position therein by the indentation (9) of the tube (1), the head having a length of approximately two times its diameter, its outer surface being in engagement with the end (2) of the tube throughout its length;

and the anvil section (7) of the pin being of smaller diameter than the head (6), and tapering from the head to the upper end of the anvil means which lies within the tube and being coated with an ignition paste, said tube and anvil section being face of any protrusions between the indented portion of the tube and the upper end of said anvil means.

2. A photoflash lamp as claimed in claim 1, wherein the anvil section extending across the percussion zone is of cone shape (10).

3. A photoflash lamp as claimed in claim 1, wherein the inner end (3) of the tube (1) at its seal to the glass envelope (4) is flared.

4. A photoflash lamp as claimed in claim 1, wherein the tube is formed with a ring groove to form the indentation thereof.

5. A photoflash lamp as claimed in claim 1, wherein

the head (6) is completely free of coating material and forms a holder for immersion in percussion material of the anvil portion only to only coat the anvil portion.
